INVENTOR.

UNITED STATES PATENT OFFICE.

EDWARD DOX KNOWLES, OF NEW YORK, N. Y.

DESIGN FOR AN EMBLEM, BADGE, MEDAL, OR ORNAMENT.

48,183.

Specification for Design.

Patented Nov. 23, 1915.

Application filed August 13, 1915. Serial No. 45,443. Term of patent 3½ years.

To all whom it may concern:

Be it known that I, EDWARD Dox KNOWLES, a citizen of the United States, and a resident of 24 West Seventy-fifth street, in the city, county, and State of New York, have invented the ornamental Design for an Emblem, Badge, Medal, or Ornament, as shown.

The figure is a plan view of an emblem illustrating my new design.

I claim—

The ornamental design for an emblem, badge, medal or ornament as shown:

Signed at the city, county and State of New York, this 19th day of October, A. D., 1915.

EDWARD DOX KNOWLES
